UNITED STATES PATENT OFFICE.

WILLIAM RIKER, OF NEWARK, NEW JERSEY.

DESIGN FOR A BANNER-PIN.

Specification forming part of Design No. 5,086, dated July 4, 1871.

To all whom it may concern:

Be it known that I, WILLIAM RIKER, of Newark, in the county of Essex and State of New Jersey, have invented a new and original Design for a Banner-Pin; and I do hereby declare that the following is a full, clear, and exact description thereof, which will enable others skilled in the art to make and use the same, reference being had to the accompanying drawing forming part of this specification, which represents a perspective view of my design for a banner-pin.

In the drawing, A represents the pendent banner or body of the pin, and B its vertical stem.

The banner and stem may bear any suitable device.

I claim as my invention—

1. The design for the pendent banner as applied to a breast-pin or badge, as shown.
2. The design for the pendent banner when affixed to an upright stem, as shown.

WILLIAM RIKER.
